FLAW DETECTOR MECHANISM

Harcourt C. Drake, Hempstead, N. Y., assignor
to Sperry Products, Inc., Brooklyn, N. Y., a
corporation of New York

Application November 1, 1933, Serial No. 696,178

8 Claims. (Cl. 175—183)

This invention relates to flaw detector mechanisms for electrical conductors, and more particularly to the type of mechanism employed in the Sperry rail flaw detector cars. The principle 5 of operation employed in said mechanism is now well known and consists in sending current through the conductor under test to establish an electromagnetic field surrounding the same and then exploring said field with induction means 10 to detect any irregularities in flux set up by the presence of flaws within the conductor. Said irregularities may be caused to induce an E. M. F. which, after being suitably amplified, may be caused to operate indicating means such as pens 15 operating on a moving chart.

Since a rail flaw detector mechanism constructed as above would pick up every rail joint in the same manner as a flaw, due to the fact that at each rail joint there are angle bars, bolts, 20 etc. which distort the electromagnetic field, means are provided in the Sperry car for cutting out the indicating means when the detector mechanism is passing over a rail joint.

In certain types of railroad construction, particularly that used on certain European railways, there is provided in addition to the rail joint angle bars, intermediate angle-bars or clamps which grip the rail and fasten it to the ties at a point between the rail joints. Such intermediate 30 clamping means would ordinarily also actuate the joint-cutout mechanism to cut out the indicating means while the detecting means was passing over the intermediate clamp. However, it is not desirable to cut out the indicating mechanism 35 at this point because it results in failure of the detector mechanism to test certain parts of the rail. Therefore, the principal object of my invention is the provision of means which would prevent actuation of the indicator cutout mechanism by means other than the rail joints.

Further objects and advantages of this invention will become apparent in the following detailed description.

In the accompanying drawing,

45 Fig. 1 is a side elevation of a portion of a Sperry rail flaw detector car to which my invention is adapted to be applied.

Fig. 2 is a wiring diagram illustrating the principle of my invention.

50 Fig. 3 is a plan view of a French type rail road construction showing an intermediate clamping member which would ordinarily operate the indicator cutout means.

Referring to Fig. 1 of the drawing, I have shown 55 a portion of the car body 10 of a Sperry rail flaw

detector car within which is located a generator G designed to supply current to sets of brushes 11 and 12 supported by a current brush carriage 15 which is designed to ride upon the rail R by means such as flanged wheels 16. The current brush carriage is adapted to be held normally in raised or ineffective position by means such as cables 17 and retractile springs (not shown) and may be lowered to effective position into engagement with the rail by means such as fluid pressure supplied to cylinders 18 to depress piston rods 19 connected to the current brush carriage. When the fluid pressure supply is cut off the retractile springs and the cables 17 will raise the current brush carriage.

The current supplied to the rail by sets of brushes 11, 12 will establish an electromagnetic field surrounding the rail and said field will be uniform except in the region of flaw. Irregularities in the electromagnetic field surrounding the rail are designed to be detected by inductive means such as a pair of coils 20 housed in housing 21 supported on a detector carriage 22 adapted to ride upon the rails on means such as wheels 23, said detector carriage being in turn supported on the current brush carriage for movement independent thereof by means of a limited universal connection comprising loose-fitting bolts 24 and springs 25. Variations in the current supply will have no effect upon the induction coils 20 because the coils are of equal inductance and oppositely connected. The coils normally cut a constant number of lines of force; but on entering a region of flaw, one of said coils will cut a different number of lines of force to generate a differential E. M. F. which, after being suitably amplified by amplifier A, may be caused to operate any suitable indicator such as pens P and P' operating on a moving chart.

The output of amplifier A operates pens P and P' by means such as relays 30, 31 which are of different strengths so that a weak flaw will cause only relay 30 to attract its armature 30' and close contacts 32 through pen relay 34, while a strong output of amplifier A due to a substantial region of flaw will cause both output relays 30 and 31 to attract their armatures 30' and 31' to close contacts 32 and 33 and actuate two pen relays 34 and 35 to actuate pens P and P'. Said pens normally trace a straight line on a moving chart but when actuated by the relays 34 and 35 they will make a jog in the line to indicate the presence of a flaw.

It will be seen that when passing over a rail joint, the detector mechanism would pick up

said rail joint and the result would be that pens P and P' would give a series of indications at each rail joint. This is undesirable since it tends to complicate the record and makes it difficult to 5 detect an indication of flaw close to the rail joint. For this reason, means are provided for cutting out the operation of pens P and P' when the detector mechanism is passing over a rail joint. Said means comprises fingers 40 and 41 in advance 10 and to the rear of the detector mechanism 20, said fingers being designed to engage the side of the rail so that they will contact with the angle-bars 42 at the rail joint. Said fingers are pivoted, as shown in Fig. 2, so that upon engagement 15 with the angle-bar at a rail joint they will close contacts 43, 44 which will close a circuit extending through a joint cutout relay 45 which will attract its armature 46 to break contacts 47, 48 which are in the line between contacts 32, 33 and the pen magnets 34, 35. At the same time that armature 46 is attracted to break contacts 47, 48, contacts 48, 49 will be made to energize a joint pen magnet 50 to operate a joint pen J which will indicate on the chart that 20 a joint has been encountered. The joint cutout fingers 40, 41 are so positioned that finger 41 engages the angle-bar 42 before finger 40 has left it, so that throughout the entire passage of the detector mechanism over the rail joint the 25 pens P and P' will be ineffective. As soon as the finger 41 has left the angle-bar the pens are again ready to operate.

In certain types of railroad construction, such as is found in France, there are clamp plates 60 for fastening the rail to a tie at an intermediate point in the length of the rail. It will now be seen that when fingers 40 and 41 engage said clamp plate 60 they will cut out the indications of pens P and P' two successive times, first, when finger 40 engages said clamp plate, and later when finger 41 engages said clamp plate. Since the clamp plate 60 is of lesser length than clamp plate 42, there will be an interval between the times that finger 40 and finger 41 render the pens 45 P and P' ineffective. Thus, there will be two parts in the intermediate section of the rail which will not be tested, i. e. the parts over which the detector mechanism passes while fingers 40 and 41 engage clamp-plate 60. Or, stated another way, although the detector mechanism passes thereover and responds to any flaws therein, such flaws will have no effect upon the pens P and P' which are temporarily rendered ineffective by the two successive operations of fingers 40 and 41 by the intermediate clamp plate. 50

To obviate the above difficulty, I provide the following means which has for its object to prevent the joint cutout mechanism from rendering the pens P and P' ineffective for a predetermined interval after a rail joint has been passed over, said interval being sufficient to allow the car to pass beyond the intermediate clamp plate. This construction takes the form of a pair of contacts 70, 71 in the circuit of magnet 45 which 60 is designed to break contacts 47, 48 to render the pens ineffective. One of said contacts 71 is part of an armature 72 designed to be attracted by delayed-action magnet 73 in parallel with the magnet 45. Contacts 70 and 71 are normally closed so that the circuit through magnet 45 will be completed by the closing of contacts 43 or 44. Another set of contacts 75, 76, normally open, are connected in parallel with contacts 70 and 71 to form a by-pass around the same. One 70 of the contacts 75 may be part of an armature

77 designed to be attracted by the rapid-acting magnet 78, likewise in parallel with magnet 45.

By the construction described above, the operation when cutout finger 40 engages the angle-bar 80 is as follows: Contacts 43 are closed and the circuit through magnets 73, 78 and 45 is closed by reason of the closed contacts 70, 71 which are delayed slightly in opening because magnet 73 is a delayed-action relay. By the time contacts 70, 71 have opened, contacts 75 and 76 have closed because relay 78 is a rapid-acting relay. Thereafter, it does not matter if contacts 70, 71 are open, the magnets 73, 78, and 45 will remain energized by reason of the fact that the circuit is now completed by way of the by-pass through contacts 75, 76. Magnet 45 attracts its armature 46 to break contacts 47 and 48 and render the pens P and P' ineffective until joint finger 41 has passed beyond the angle-bar.

When said joint finger 41 has passed beyond the angle-bar, the circuit through magnets 73, 78 and 45 is broken and the armature 46 returns to its original position to close contacts 47, 48 and render the pens P and P' again effective. Contacts 75 and 76 also open. Contacts 70 and 71 do not close, however, for a predetermined interval of time, by reason of the fact that armature 72 is connected to a delayed-action mechanism such as a one-way dash-pot 80 which will delay the closing movement of contact 71 toward contact 70 for an interval of time which is determined by the rate of travel of the car over the rails and the distance between angle-bar 42 and clamp plate 60. Said dash-pot is adjusted so that contacts 70 and 71 will close when the car has passed substantially beyond clamp plate 60. Thus, it will be seen that even though fingers 40 and 41 engage the clamp plate to close contacts 43 and 44, magnet 45 is not energized to attract armature 46 because the circuit through magnet 45 is open at points 70 and 71. 100

Not only will the above described mechanism prevent rendering the pens P and P' ineffective by a central clamp plate, but it will also prevent operation of the joint fingers 40 and 41 by means of overhanging pieces of rail which have become detached from the main railhead. In fact, the period of time which elapses before contacts 70 and 71 close may be so adjusted that once contact finger 40 has closed contacts 43, contacts 70 and 71 will not close again until substantially a rail length has been covered, that is, until contact finger 40 is within striking distance of the next angle-bar 42. Thus, any factors along 110 the railhead which would tend to operate the joint cutout fingers will not be effective to cut out pens P and P', but only the angle bars 42 at the rail joints will have such effect. 115

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. In a flaw detector car adapted to travel

- along the rails, the adjacent rails being joined together, means responsive to flaws, indicating means, means whereby said responsive means actuates said indicating means, means adapted to 80
- 5 cooperate with the rail joint for rendering said actuating means ineffective when said responsive means passes over a rail joint, and means for preventing said cooperating means from again rendering said actuating means ineffective for 85
- 10 a predetermined interval after said cooperating means has passed out of cooperative relation with the rail joint.
2. In a flaw detector car adapted to travel along the rails, the adjacent rails being joined together, means responsive to flaws, indicating means, means whereby said responsive means actuates said indicating means, joint cut-out members adapted to engage the rail joint for rendering said actuating means ineffective when said responsive means passes over the rail joint, and means for preventing said members from again rendering said actuating means ineffective for a predetermined interval after said members have passed beyond the rail joint. 90
- 25 3. In a flaw detector car adapted to travel along the rails, the adjacent rails being joined together, means responsive to flaws, indicating means, means whereby said responsive means actuates said indicating means, means adapted to 95
- 30 to cooperate with the rail joint for rendering said actuating means ineffective when said responsive means passes over a rail joint, and means for preventing said cooperating means from again rendering said actuating means ineffective for a predetermined interval after said members have passed out of cooperative relation with the rail joint, said last-named means including an electric circuit normally effective to be energized by said cooperating means when in cooperative relation with the rail joint, means whereby said cooperating means energizes said circuit 100
- 35 when in cooperative relation with the rail joint, means actuated by said cooperating means when in cooperative relation with the rail joint for rendering said circuit ineffective when said cooperating means has passed out of cooperative relation with the rail joint, and delayed action means for rendering said circuit effective. 105
- 40 4. In a flaw detector car adapted to travel along the rails, the adjacent rails being joined together, means responsive to flaws, indicating means, means whereby said responsive means actuates said indicating means, means adapted to 110
- 45 cooperate with the rail joint for rendering said actuating means ineffective when said responsive means passes over a rail joint, and means for preventing said members from again rendering said actuating means ineffective for a predetermined interval after said members have passed beyond the rail joint, said last-named means including an electric connection, means 115
- 50 whereby said connection is broken when said members engage the rail joint, and delayed action means for re-establishing said connection. 120
- 55 5. In a flaw detector car adapted to travel along the rails, the adjacent rails being joined together, means responsive to flaws, indicating means, means whereby said responsive means actuates said indicating means, joint cut-out members adapted to engage the rail joint for rendering said actuating means ineffective when said responsive means passes over the rail joint, and means for preventing said members from again rendering said actuating means ineffective for a predetermined interval after said members have passed beyond the rail joint, said last-named 125
- 60 means including an electric circuit normally effective to be energized when said members engage the rail joint, means whereby said circuit is energized when said members engage the rail joint, means actuated by said members when in 130
- 65 engagement with the rail joint, for rendering said circuit ineffective when said members have passed beyond the rail joint, and delayed action means for rendering said circuit effective. 135
- 70 6. In a flaw detector car adapted to travel along the rails, the adjacent rails being joined together, means responsive to flaws, indicating means, means whereby said responsive means actuates said indicating means, means adapted to cooperate with the rail joint for rendering said actuating means ineffective when said responsive means passes over a rail joint, and means for preventing said cooperating means from again rendering said actuating means ineffective for a predetermined interval after said cooperating means has passed out of cooperative relation with 140
- 75 the rail joint, said last-named means including an electric circuit, a circuit-controlling device in said circuit for normally closing the same, means whereby said cooperating means when in cooperative relation with said rail joint actuates said device to open the circuit, and delayed action means for delaying the return of said device to normal position. 145
